UNITED STATES PATENT OFFICE.

RANSOM M. ELKINS, OF POPLAR BLUFF, MISSOURI.

RINSING-FAUCET.

1,023,630.

Specification of Letters Patent. Patented Apr. 16, 1912.

Application filed March 8, 1910. Serial No. 547,960.

To all whom it may concern:

Be it known that I, RANSOM M. ELKINS, a citizen of the United States, and a resident of Poplar Bluff, in the county of Butler and

5 State of Missouri, have made certain new and useful Improvements in Rinsing-Faucets, of which the following is a specification.

10 My invention is an improvement in rinsing devices, designed for rinsing various kinds of hollow utensils such as bottles, jugs, tumblers, fruit jars, milk jars or bottles, and the invention has for an object among others to provide a simple, novel construction of washer, being so constructed that the rinsing device will not interfere with the normal operation of the faucet proper and the latter may be operated for its usual purpose independently of the rinsing device.

15 The invention consists in certain novel constructions and combinations of parts as will be hereinafter described and claimed.

20 In the drawings, Figure 1 is a sectional view of the apparatus embodying my invention, a portion of the outside washer being broken away and the rinsing valve being shown closed; Fig. 2 is a section similar to Fig. 1, the rinsing valve being shown open and the outside washer being omitted; Fig. 3 is a top plan view of the faucet proper, detached from the rinsing devices; Fig. 4 is a side view of the bottle washer; Fig. 5 is a perspective view illustrating the bottle washer nozzle, together with the valve plug 25 and the coupling collar; Fig. 6 is a detail perspective view of the nozzle tube for tumblers; Fig. 7 is a side view partly broken away and partly in section, illustrating the outside washer; and Fig. 8 is a sectional view showing the faucet with a wire cloth thimble designed to break the force of the water and prevent splashing when the apparatus is used in connection with soda fountains, bars and drink stands.

30 An important feature of my invention is that the improvement may be attached to a water supply and the rinsing device may be used whenever desired without dispensing with the convenience afforded by the 35 water supply in connection with the faucet. In doing this, I find it necessary to employ a special form of bib faucet in order that the latter may not be interfered with in its opening movement by devices forming a 40 part of the rinsing attachment, as otherwise the rinsing attachment would interfere with

the operation of the bib faucet and the latter would interfere with the operation of the rinsing device, all of which will more fully appear hereafter.

45 In carrying out the invention, I form the rinsing device with a casing A which may be connected at B with the water supply system and has the main chamber A' provided at its upper end with a valve seat A² for the rinsing plug valve C, and the bottom of said chamber is formed with a movable plug D threaded in place so it can be conveniently moved when desired, and having in its upper end a socket D' for the depending stem C' of the valve C. The valve C is fitted to its seat A², the latter made in the form of a socket as shown in Figs. 1 and 2 so that the valve C when seated therein fills the socket and seats at both its upper end 50 and at its sides, and a spring E between the plug valve C and the plug D presses the valve C normally to closed position as shown in Fig. 1. The valve C has the upwardly projecting valve tube C² formed integrally with it and is provided adjacent to the valve C with openings C³ through which the water may be circulated, as shown in Fig. 2, when the valve C is open. At its upper end the tube C² has a reduced portion 55 C⁴ and immediately below the same is provided with external threads C⁵ to receive the coupling collar F, which screws on the threads C⁵ and projects above the shoulder C⁶ formed at the base of the reduced portion 60 C⁴ so that the lower end of the nozzle tube G which fits on the reduced portion C⁴ may screw into the coupling collar F at the upper side of the latter.

65 The collar F may preferably be formed as best shown in Fig. 5 so that it will form a stop for a bottle when placed thereon as shown in Fig. 4 and yet will afford passages for the escape of water alongside of the arms F' of the collar. By this construction, it will be noticed, the parts may easily be assembled by inserting the valve C with the spring E on its stem C' up through the open bottom end of the casing A and applying the plug D to secure the said parts, after 70 which the coupling collar and the rinsing nozzle may be applied as shown in Fig. 2.

75 The nozzle tube G shown in Figs. 1, 2 and 6 has at its upper end a flared nozzle G' whose top plate G² is perforated for the discharge of water, and short projecting lugs G³ project above the top plate G² to form a

bearing for the tumbler and permit the discharge of water into the tumbler, as best shown in Fig. 2 of the drawing.

The nozzle G' operates to wash the inside 5 of the glass or tumbler, and for washing the outside thereof I provide a washing tube H, preferably in the form of a flattened ring connected with the inside nozzle and adapted to encircle a tumbler fitted on said tube 10 as shown in Fig. 7 and having on its inner side at its upper, portion, openings at H² for discharging water upon the glass. This outside ring washer has at its top a knob H³ which may be grasped in depressing the device 15 after a tumbler has been placed on the nozzle tube G as shown in Fig. 7.

The described devices are adapted for use in washing tumblers or other vessels whose necks can be conveniently entered by the 20 nozzle G', and I may preferably employ in connection with the inside nozzle tube the outside ring tube H as illustrated in Figs. 1 and 7, or, if desired, in some cases the outside ring tube may be omitted as illustrated 25 in Fig. 2, but it will be noticed that in both of said constructions the operation of the rinsing device in no way interferes with the operation of the bib valve, more fully described hereinafter.

30 For use in rinsing bottles, as shown in Fig. 4 or other vessels having comparatively contracted necks, I may use the special form of nozzle tube I shown in Figs. 4 and 5, with the nozzle I' adapted to discharge water to 35 wash the interior of the bottle.

The faucet J is threaded at J' to screw into the casing A, and has at the end of its threaded portion a valve seat J² for the semi-spherical valve K carried on the stem 40 L arranged for operation by the handle L',

as will be understood from Figs. 1, 3 and 4 of the drawings. Manifestly, the arrangement of the valve-operating device may be varied, and that shown in Fig. 8 may be employed if desired.

The valve is formed with the concavo-convex body porton J and the brass cap M forming a reinforce for the rubber or other suitable concavo-convex body, and having a depression M' at its center to receive the head of the securing screw N, as best shown in Figs. 1 and 8 of the drawing. By this construction I provide a bib valve whose end next the rinsing device is flattened so that the bib valve may be opened to its fullest extent without interfering with the construction in any way or with the operation of the rinsing devices or vice versa.

In Fig. 8 I show a wire cloth thimble N, 60 the purpose of which is to break the force of the water and prevent splashing when the device is used with soda fountains, bars and drink stands.

I claim:

The combination in a rinsing apparatus of a valve tube, a collar applied to said tube and adapted to coöperate in connecting nozzle tubes therewith, the said collar being adapted to form a stop for a bottle when placed thereon and having cut away portions in its sides forming passages for the escape of water from a bottle placed against said collar, and a nozzle tube in connection with said collar and valve tube, substantially 75 as set forth.

RANSOM M. ELKINS.
